UNITED STATES PATENT OFFICE.

EDWARD J. SCHUH, OF SPOKANE, WASHINGTON.

MACHINE FOR MAKING CONCRETE PRODUCTS.

Application filed February 28, 1923. Serial No. 621,813.

To all whom it may concern:

Be it known that I, EDWARD J. SCHUH, a subject of the King of Great Britain, residing at Spokane, in the county of Spokane and State of Washington, have invented new and useful Improvements in Machines for Making Concrete Products, of which the following is a specification.

This invention relates to an improved mechanism for making concrete products.

My invention has to do with an improved feeder for advancing the concrete mud toward a mold in which the mud is formed in accordance with the product to be produced. My improved feeder includes a container or hopper for the mud having a discharge opening delivering to the mold, and a tamper movable through the hopper into the mold. During the strokes of the tamper, feeding or advancing means intermittently advances the mud toward said discharge opening, said means acting not only on the active but also on the inactive strokes of the tamper.

It is a feature of my invention to provide means for driving the tamper, which means operates in a fixed path of travel, and which means is connected with the tamper in such a manner that the strokes of the latter can gradually decrease as the mold is filled.

In order to insure a product of uniform density, I make the product of one dimension initially greater than it will be in final form, and shear off the surplus so that the final product will have a smooth and unbroken top surface.

It is a further feature of my invention to reduce or provide a tamper of a lesser cross section than the mold or the discharge opening in the hopper whereby the thrust of the tamper, downwardly, will serve to spread and pack the mud laterally in the mold to the full tamping height.

An important feature consists in providing mud feeding means on opposite sides of the tamper whereby the mud will be uniformly and most effectively advanced theretoward, means being provided in advance of the tamper for controlling the flow or passage of the mud thereto.

Another phase of my invention has to do with an improved mold structure in which the product is formed.

My invention has many other features and

objects which will be more fully described in connection with the accompanying drawings and which will be more particularly pointed out in and by the appended claims.

In the drawings:

Fig. 1, is a view in elevation of my improved device showing the tamper in an upward position.

Fig. 2, is a similar view showing the tamper in a lower position.

Fig. 3, is a vertical sectional view on a slightly enlarged scale with the parts in a position similar to Fig. 1.

Fig. 4, is a similar sectional view with the parts in the position shown in Fig. 2.

Fig. 5, is a sectional view on line 5—5 of Fig. 3.

Fig. 6, is a view illustrating the tamper operating means with the tamper in a lower position.

Fig. 7, is a view similar to Fig. 6, showing the position of the tamper after the mold is partly filled.

Fig. 8, is a position showing the tamper in an extreme upward position.

Like characters of reference designate similar parts throughout the different figures of the drawings.

Referring first to Fig. 6, 1 designates a mold body of which there may be a plurality adapted to be advanced into and out of registry with a container or hopper 2. The means and mechanism for performing this advancing operation is not herein specifically claimed and shown in detail, and as far as this disclosure is concerned, the same may consist broadly, of an advancing platform 3, having means as indicated at 4, to advance the platform, which may either be circular and be rotated or traverse a linear path of travel. At any rate, the platform 3, and the wheel 4, may be considered advancing means for the mold body or bodies.

The container or hopper 2, is stationary and may be supported by any suitable means, (not shown) in a delivery position with respect to the mold bodies. A tamper 5, which I will now merely broadly refer to extends upwardly from the hopper and in driven relation with means which is preferably designed to impart reciprocating movement to the tamper, and which means is broadly indicated at 6.

With this prefatory and general descrip-

tion of the relation of the various integers of the mechanism completed, I will next specifically describe the feeding mechanism, reference being had more particularly to 5 Figs. 1 to 5.

The hopper 2, as shown, has vertical side walls 7, and converging end walls 8, which latter are shown as being inclined downwardly from the top of said hopper toward a discharge opening 9. It will be noted that this discharge opening is embodied in a discharge extension 10, at the lower end of the hopper, this extension, as shown, having vertical interior walls 12, which are coextensive with, or in other words, register with the cavity in the mold body so as to form a vertical extension thereof in delivery relation thereto. Thus, because of this discharge extension, the resulting product will initially have a greater height than when in its final form, the importance of this feature being more fully developed later on.

The tamper 5, reciprocates in guides 13 and 14, and it will be noted that in cross section, the tamper 5 does not fill the opening 9 or the mold body 1, there being a considerable clearance, as will be clearly seen by reference to Figs. 4 and 5. Thus, the tamper exerts its main tamping action centrally of the mold 1, the clearance space laterally of the tamper affording lateral movement of the mud so that the product will have a uniform density such that it can be safely handled after being removed from the mold and prior to setting of the concrete. This is a special feature of my invention. This lateral shifting of the mud into the side and end clearance spaces obviously amounts to a packing function, and it will now be clear that the tamper not only packs the mud subjacent to its lower end face but it also packs the mud laterally against the vertical side walls of the mold. Hence, the packing or tamping is carried out internally of the outside faces of the product to be formed, and that is one reason why the resulting product is uniform in density. The tamper 5, is actuated by means later described, to reciprocate vertically in a gradually decreasing length of stroke dependent upon the extent of fill or pack of the mud in the mold, the lower position being shown in Fig. 4, and the upper position in Fig. 3. In order to limit the movement of the mud in hopper 2, into the mold 1, I provide means which may take the form of gates 15, one on each side of the tamper. These gates are adjustable vertically in guides 16, and may be frictionally or otherwise locked in their adjusted positions. However, an important feature is that they restrict the passage of mud at a point or points in advance of the discharge opening from both sides of the tamper 5.

and thereby afford the latter free movement between the same. It will be seen that these gates extend upwardly in the hopper sufficiently to form partitions to prevent the mud from engaging the tamper laterally or 70 endwise, and frictionally resisting movement of the tamper.

It will be understood that concrete mud can not be advanced by gravity, as it is too thick to flow, and it will also be understood 75 that the speed in making a concrete product is primarily dependent upon the rapidity with which the mud is fed. Now it is a primary object of this invention to attain a high speed of manufacture and one of the 80 important features consists in means for rapidly feeding the mud in the hopper toward the opening 9, which means I will next describe in detail.

Feeders are preferably provided in the 85 form of bars 17 and 18, the former of which may be linearly movable and the latter of which are preferably floating bars. It will be seen that a set of bars is provided on each side of the tamper and in the preferred construction, one set moves upwardly 90 while the remaining set moves downwardly, and the arrangement is such that one set of these alternately moving bars moves in synchronism with the tamper and the other 95 set in alternation with the tamper, as will be later described. The bars 17, have mud thrusting faces 19, which are inclined with respect to the direction of movement of the bars. Thus, the bars do not thrust the mud 100 downwardly in the manner of a flat faced bar, or one having a face at right angles to the path of movement. Likewise, the upper face 20, is inclined with respect to the path 105 of movement, thereby facilitating release of the mud on the upward stroke. In short, the bars have a triangular cross section with sharp upper and lower edges 21 and 22 which serve to cut through the mud on both working and return strokes. Likewise, 110 the bars 18, have mud thrusting faces 23, which are inclined with respect to the path of travel, and rear faces 24, similarly inclined, the broad faces 25, resting on the walls 8. An advantage resulting from the 115 triangular cross section of the feeders, as embodied in the inclined faces 23 and 24, is that the feeders tend to cling toward, instead of being shifted away, from the inclined wall of the hopper. In other words, 120 as the feeder descends, the inclined face 23, seeks to move under the mud while advancing the same, and thus, the weight or reacting thrust of the mud holds the feeder 125 against the hopper wall. The same is true on the return stroke. Now because of this construction, I do not have to employ guiding means for the feeders which means would inevitably clog with mud. It will also 130 be noted by reference to Figs. 3 and 4, that

feeders 17, intersect the path of travel of feeders 18, and vice versa, thereby preventing the mud from arching as the mud is advanced toward the discharge opening.

5 Now with this form of feeder, and with one set of feeders operating in a path of travel angular to that of the other, and in alternation, as set forth, I not only attain a very rapid but a most effective feed of 10 the mud.

I will next describe the manner and means of operating the tamper and feeder bars, reference being had to Figs. 1 and 2, and 6 to 8.

15 Each feeder 17 has a pair of bars 26 rigidly attached to the ends thereof and extending upwardly between guides 27. Each feeder 18, has a pair of bars 28 rigidly attached thereto and extending outwardly 20 along end walls 8. Rocker bars 29 are adjustable and pivotally connected with bars 28, at 30. The opposite ends of these rocker bars 28 are pivoted at 31, to an actuating sleeve or member 32, to be later described.

25 Bars 26, are pivoted to rocker bars 29, at 33. Thus, as the driving member 32, reciprocates, the rocker bars 29, impart reciprocating movement to the feeders. In order to impart alternating movement to said feed-

30 ers, as previously described, I pivotally mount said rocker bars 29, at 34, to floating bars 35, the latter being adjustably pivoted at 36, to the hopper. The range of movement imparted to feeders 18, may be readily 35 varied by changing the pivotal connections at 30 or 34. It will now be clear that in the absence of any guides to feeders 18, except the walls 8, that the latter are float-

40 ing feeders, the inclined faces 23 and 24, alone, serving to retain said feeders closely adjacent walls 8. Further, it will be understood that as the member 32, rises, the feeders 17 will rise and the feeders 18 will descend. Thus, a substantially continuous 45 feeding thrust will be imparted to the mud to advance the latter for tamping action as rapidly as required. The gates 15, may be relied upon to control the feed, in addition to adjustment of the bars to control the 50 stroke of the feeders.

Next referring to Figs. 6 to 8, showing the means for reciprocating the tamper, it will be seen that the member 32 is shown in the form of a sleeve, which is slidably connected 55 with tamper 5. A stop 37, on tamper 5, is adapted to coact with shoulders 38 of the sleeve, formed as a result of an enlargement of the sleeves as indicated at 39. One or more contractile springs 40, have their lower 60 ends 41, connected with said sleeve, and their upper ends 42, connected with a pin 43, carried by the tamper 5. The upper end 44, of said sleeve is suitably connected with a cross head 45, slideable in guides 46. A connecting rod 47 has its lower end pivoted at

48, to said sleeve, and its upper end connected at 49, to a disc crank 50, mounted on shaft 51. This shaft 51, may be belted, as at 52, to be driven from any suitable source of power.

It will now be clear that while the sleeve 32, partakes of a fixed path or extent of movement, the springs 40, will yield and permit the tamper to reduce its stroke as the mold fills. Thus, in Fig. 6, the mold 1, 70 is just starting to fill and the springs 40 have only yielded slightly and therefore the stop 37, is only slightly out of contact with shoulders 38. In Fig. 7, wherein the mold is 75 more nearly filled, I have shown the tamper 80 at a higher elevation with the stop 37 in further spaced relation to shoulders 38 and the springs 40 tensioned to a further extent. These two figures show the sleeve 32, in the full down stroke position. In Fig. 8, I 85 have shown the parts in a full upstroke position with shoulders 38, in engagement with stop 37. Now it will be clear that the tamper 5, always moves to the same upward position with sleeve 32, but the downward 90 stroke of tamper 5, is shortened as the mold fills. By reason of this spring connection, I obtain, in addition to the initial impact of the tamper, a yielding and sustained pressure on the mud following such initial impact, such sustained pressure being held as the center 49 passes over the position shown in Fig. 6. It will also be noted that on each upward stroke, the tamper is elevated above 95 the discharge or molding extension 10. 100 Now, by again referring to Figures 3 and 4, I will explain the importance of this molding extension.

I have indicated by dotted line 53, the height level to which the mud will be 105 tamped. This is slightly above the top of mold 1, hence the product, which as shown is a brick, will be, in practice, one inch greater in this vertical dimension. When the brick has been fully tamped, the tamper 5, will be arrested and the platform 3, will be advanced to the extent of moving the mold 1, just filled, out of registry with extension 10, and moving the next mold 1 into registry therewith. Now in moving the 110 filled mold 1, out of registry with extension 10, I shear off that portion of the tamped material in extension 10, from the remainder of the brick, thereby leaving the latter 115 smooth and finished on top thereof, the brick 120 also having a uniform density throughout its cross section. Hence, it will now be clear that I do not tamp merely to a level equal to the top of the mold, but to a higher level so that should there be any slight lack 125 of uniformity, it will be in the extension 10, not in the mold 1. In order to prevent wasteful discharge from hopper 2, as one mold is being advanced and until another 130 mold is into registry with said hopper, I

provide the molds 1, with closure plates 54, which close the extension 10, until the next mold is in place.

While this feeding mechanism is especially adapted for brick molding machines, it is not limited to this utility but is advantageous in any mud feeding capacity wherein speed is an important factor.

While I have shown one specific form of my invention, I do not wish to be limited thereto except for such limitations as the claims may import.

I claim:—

1. A device for rapidly feeding concrete mud into a mold, comprising in combination, a mold, a hopper in delivering relation to said mold, a tamper movable through said hopper into said mold to tamp the mud therein, and sets alternately movable of feeders on opposite sides of said tamper for substantially continuously advancing the mud toward the latter.

2. A device for rapidly feeding concrete mud toward a mold, comprising in combination, a mold, a hopper in delivering relation to said mold, a tamper movable through said hopper into said mold to tamp the mud in the latter, and sets of feeders on opposite sides of said tamper, each set comprising alternately actuated feeders substantially continuously feeding the mud.

3. A device for rapidly feeding concrete mud toward a mold, comprising in combination, a mold, a hopper for the mud in delivering relation to said mold, a tamper movable through said hopper into said mold to tamp the mud into the latter, and a guided and a floating feeder for advancing the mud toward said tamper.

4. A device for rapidly feeding concrete mud into a mold, comprising in combination, a mold, a reciprocating tamper movable through a hopper into said mold, a floating and a guided feeder in said hopper, and floating means operated by said tamper for actuating said feeders.

5. A device for rapidly feeding concrete mud into a mold, comprising in combination, a mold, a hopper for the mud in delivering relation to said mold, a reciprocating tamper movable through said hopper into said mold, a feeder in said hopper movable in parallel relation to said tamper, and a feeder in said hopper movable in angular relation to said tamper.

6. In a device for feeding concrete mud into a mold, comprising in combination, a mold, a hopper for the mud having a discharge opening registering with said mold, a tamper of reduced cross section with respect to said opening and movable therethrough into said mold, means for advancing the mud in said hopper toward said opening, and an adjustable gate for variously restrict-

ing the volume of mud passing toward said opening.

7. A device for molding concrete products such as bricks, comprising in combination, a mold, a hopper for the concrete mud disposed in discharging relation to said mold, a tamper movable through said hopper into said mold, and means for actuating said tamper movable through a fixed path and permitting yielding retraction of said tamper while the latter is operating from said mold into said hopper as the mold is tamped full.

8. A device for molding concrete products such as bricks, comprising in combination, a mold, a hopper for the concrete mud disposed in discharging relation to said mold, a reciprocable tamper movable through said hopper into said mold, and reciprocating means having a fixed length of travel and in yielding driving connection with said tamper and permitting gradual decreasing strokes of said tamper as the mold is filled.

9. A device for molding concrete products such as brick, comprising in combination, a mold, a hopper for the concrete mud disposed in delivering relation to said mold, a reciprocating tamper movable through said hopper into said mold, a reciprocating driver for said tamper, and springs connecting said driver with said tamper to impart a yielding tamping stroke to said tamper and permit the tamper to gradually shorten its stroke as the mold is filled.

10. A device for rapidly feeding concrete mud, comprising in combination, a hopper for the mud having a discharge opening, and a movable feeder in said hopper for advancing the mud toward said opening, and said feeder having forwardly and rearwardly disposed faces at an inclination to the path of movement of said feeder.

11. A device for rapidly feeding concrete mud, comprising in combination, a hopper for the mud having a lower wall and a discharge opening toward which said wall leads, and a feeder bar movable along said wall, and said bar having a front face inclined rearwardly with respect to the direction of forward movement of said bar.

12. A device for rapidly feeding concrete mud, comprising in combination, a hopper for the mud having a discharge opening and a lower wall leading toward said opening, and a feeding bar movable along said wall toward and from said opening, said bar having forward and rearward faces inclined with respect to the direction of movement of said bar.

13. A device for rapidly feeding concrete mud to a mold, comprising in combination, a mold body, a hopper for the mud having a discharge opening delivering to said mold, a tamper movable upwardly and downwardly

- in said mold and hopper, a feeder movable downwardly on downward movement of said tamper to advance the mud toward said opening, and a feeder movable downwardly on upward movement of said tamper to advance the mud toward said opening.
14. A device for feeding concrete or like mud, comprising in combination, a mold, a hopper for the mud and in delivery relation to said mold, gates dividing off said hopper and restricting flow of the mud toward said mold, a tamper between said gates for tamping the mud into said mold, and devices between said gates and the walls of the hopper for advancing the mud past said gates and toward said mold.
15. A device for feeding concrete mud or the like comprising, a mold, a container for the mud in delivering relation to said mold, and a tamper extending through said container into said mold and being of such reduced cross section with respect to the interior of the mold that said tamper will pack the mud laterally as well as downwardly.

In testimony that I claim the foregoing as my own, I hereby affix my signature.

EDWARD J. SCHUH.
